UNITED STATES PATENT OFFICE.

ALFRED F. McCOLLUM, OF BLOOMSBURG, PENNSYLVANIA, ASSIGNOR OF THREE-FIFTHS TO JAMES MAGEE, 2D, OF BLOOMSBURG, PENNSYLVANIA.

FEEDING MECHANISM.

1,257,900.

Specification of Letters Patent. Patented Feb. 26, 1918.

Application filed October 16, 1914. Serial No. 866,973.

To all whom it may concern:

Be it known that I, ALFRED F. McCOLLUM, a citizen of the United States, residing in Bloomsburg, Pennsylvania, have invented certain Improvements in Feeding Mechanism, of which the following is a specification.

One object of my invention is to provide a sewing mechanism particularly designed to facilitate the seaming and binding of fabrics such as rugs, carpets and curtains which are difficult to handle and especially those of the type described and claimed in my Patents Nos. 1,049,119 and 1,049,120, 15 of December 31, 1912.

This object and other advantageous ends I attain as hereinafter set forth reference being had to the accompanying drawings in which,

Figures 1 and 2 are respectively a side elevation and a plan of my invention;

Fig. 3 is an enlarged elevation of a portion of the mechanism shown in Fig. 1;

Fig. 4 is a transverse vertical section 25 taken on the line $a-a$, Fig. 3;

Fig. 5 is an elevation showing a portion of my invention as applied to a sewing machine head; the latter being shown in dot-and-dash lines;

Figs. 6, 7 and 8 are enlarged vertical sections taken on the line $b-b$, Fig. 5, showing several of the parts in certain of the positions which they occupy during the operation of the machine; and

Figs. 9 and 10 are perspective views showing certain features of my invention.

In Figs. 1 to 4 of the above drawings, the support or table for the fabrics to be sewed consists primarily of a frame 1 having two side members 2 and 3 connected by transversely extending tie rods 4 and providing bearings for a series of rollers 5. The side members 2 and 3 are inclined longitudinally as shown in Fig. 1 and are supported by standards 6 each made in two sections 7 and 8 and adjustably secured together by clamps 9.

The rollers 5 taper inwardly from each end and are of the smallest diameter at the middle. A guiding rail 10, which is designed to support the edge of the fabric, (see Fig. 9) is discontinued between suitable points 11 and 12 to provide room for a table 13 which forms a support for the sewing machine head 14 (see Figs. 1, 2 and

3). This table is inclined at substantially the same angle as the side members, the series of rollers 5 and rail 10 and forms the support for the edge of the fabric while it is being passed under the sewing machine 60 head 14, being hinged at 15 and 16 to the legs 17 which are adjustably secured by bolts 18 to feet resting upon a floor.

The sewing machine head may be of any suitable type and I have therefore, only 65 shown such part of the mechanism therein as co-operates with or forms a part of my invention; the mechanism for actuating the needle, presser foot, and shuttle being omitted for sake of clearness. The feeding mechanism and the mechanism for varying the length of stitch is however illustrated, and consists of a shaft 19 carrying an eccentric 20 operative within a strap 21 70 slidable between two arms 22 of a lifting 75 or actuating lever 23. This lever is pivotally connected at 24 to one end of a link 25 whose opposite end is pivotally connected to one arm 26 of a bell-crank lever 27 which is fulcrumed at 28 to the head of the machine (see Figs. 6, 7 and 8). The pivotal points of the lever 23, the link 25 and the bell-crank lever 27 are so positioned that a rotary movement of the eccentric not only oscillates said first lever laterally as indicated by the double-headed arrow a' but will also give it an up and down movement 80 because of the swinging of the link 25 on the pivot connecting it to the bell-crank 85 lever. 90

The toothed fabric-feeding rack 30 is connected by means of a lever 21 to a shaft 32 rotatably mounted under the bed 33 of the machine head, there being on said shaft a crank or eccentric portion 32* on which 95 is mounted an arm 29 pivotally connected to the lower end of the lever 23. With this arrangement of parts an up and down movement of the lever 23 will impart a substantially horizontal reciprocating movement to 100 the feeding rack 30, which at the same time will receive a vertical movement from an arm 34 fixed on a shaft 35 which is oscillated by any suitable form of mechanism (not shown) forming no part of this invention. This arm 34 preferably has an antifriction roller 36 operative in a slot 37 in the lower portion of the toothed rack. 105

If the bell-crank lever 27 is moved from the position shown in Fig. 6 to the position shown 110

in Fig. 7 the pivotally supported end of the link 25 will be raised so that when the eccentric 20 is rotated the path of movement of the pivot point 24 is such that the vertical movement of the lever 23 is materially greater than when the bell-crank lever is in the position shown in Fig. 6. This increase in the throw of the lever 23 produces an increased movement of the feeding rack 30 and thereby tends to feed a greater amount of the fabric under the needle for each reciprocation than before the above adjustment.

For the purposes of driving the machine an electric motor 38 is secured to the under side of the table and drives a pulley 39 on the shaft 19 through the medium of belts 40 and 41 and a friction clutch 42, which in the present instance consists of two disks 43 and 44 respectively connected by said belts to said pulley 39 and to the motor. The disk 43 is moved into and out of contact with the disk 44 by means of a lever 45 pivoted at 46 to the under side of the table 13. This lever 45 is normally held in its upper position by a spring 46 secured to said table 13 and it is also connected by means of a spring 47 to a treadle 48 pivotally mounted on the legs 17 (Figs. 1, 3 and 4).

At one end the treadle has a bracket 49 in which is a slot 50 for the reception of a pin 53 projecting from a link 51 on a chain 52. The upper end of said chain is secured to the lower end of the rod 54 slidable through the table 13 and having a compression spring 55 confined between said table and a nut 56 on said rod. The upper end of this latter is movably connected to a threaded arm 57 screwed into the arm 58 of the bell-crank lever 27. With this combination of parts, after the treadle 48 has been moved downwardly a certain distance the pin 53 will engage the upper end of the slot in the bracket 49, after which the continued downward movement of said treadle will pull the chain downwardly and with it the rod 54 and arm 57 thereby turning the bell-crank lever 27 on its pivot throwing upwardly the arm 26 for the purpose previously noted.

The rugs or other fabrics, which are to be seamed or bound at the edges are first rolled as shown at α in Fig. 9 and are then placed upon the rollers 5 at the left hand end of the machine, as shown in Fig. 1. These rollers 5 are freely rotatable and the rug, due to its own weight, moves downwardly on the guideway, thus provided, to and past the sewing machine head where the operator guides the edge to be sewed under the sewing needle.

In order to prevent the rug from moving downwardly when it is not desired as, for example when the machine is not running, a brake is provided which consists of a strap 58 having one end secured at 59 to the under

portion of the rail 10 and extending alternately under and over a suitable number of the rollers (Figs. 1 and 3). Its other end is secured at 60 to one arm 61 of a lever 62 pivoted on a shaft 63 carried by the legs 17. The second arm 64 of this lever is connected by a link 65 to the treadle 48, while a tension spring 66 extending between the floor and the arm 61 tends to keep the strap 58 taut and in contact with the rollers 5 as well as assists in keeping the treadle 48 normally raised.

The table 13 is so positioned that the operator may sit in a position indicated at χ , Fig. 2, so as to face the sewing machine head 14.

Under conditions of use the motor 38 is started with the clutch disks 43 and 44 disengaged so that the sewing machine is not in action. The rolls α of fabric are then placed on the uppermost rollers 5 with their outer edges γ resting on the top surface of the rail 10 (Fig. 9). After placing the extreme forward end of said edge under the needle of the sewing machine the operator presses downwardly on the treadle 48 thus releasing the brake by pulling down on the link 65 and arm 64 against the action of the spring 66, and allowing the roll of fabric to move downwardly by gravity over the rollers 5 to the needle. This downward movement of the treadle also turns the lever 45 through the spring 47 and thereby brings the two clutch disks 43 and 44 into engagement to cause operation of the sewing machine which stitches the fabric as desired. The chain 52 up to this time has not been affected, owing to the free movement of the pin 53 in the slot 50, and the rod 54 and arm 57 are kept in their uppermost positions by the action of the spring 55 so that the bell-crank lever is held in the position shown in Fig. 6 to cause the sewing machine to form comparatively short stitches. The continued downward movement of the treadle 48 however will bring the upper end of the extension 49 into engagement with the pin 53 on the link 51 and thereby move the chain 52, rod 54 and arm 57 downwardly to cause lengthening of the stitches. In view of the fact that the machine is running during this movement of the stitch varying mechanism it is obvious that an edge can be bound and a seam can be formed similar to that described and claimed in my Patent, No. 1,049,119, dated December 31, 1912.

It will be further noted that in my present invention a single continued downward movement of the treadle 48 is made to perform three separate and distinct operations; to wit, it releases the brake on the rollers and thereby allows the fabric to automatically feed to the sewing machine; second, it starts the sewing machine; and third, it effects variation in the length of the stitches pro-

duced. After the treadle 48 has been released by the operator it will be automatically raised by the springs 47 and 66, and the latter of these will then automatically 5 act to apply the brake. The spring 55 will move the rod 54 and bar 57 upwardly to again affect the shortening of the stitches and retain the actuating lever in its normal position, while the spring 46^a will tend to 10 draw the friction clutch disk 43 out of engagement with the disk 44 and thereby stop the operation of the sewing machine.

A number of rolls of fabric such as rugs may be placed on the frame 1 at the same 15 time so that it is possible for the operator to sew them successively without stopping the machine. If it be desired to apply a binding strip to the edges of the rugs, etc., they may be placed on the rollers end to end with but 20 short spaces between them, and a continuous strip of binding can be sewed to two or more of them without stopping the machine, after which they may be separated by merely cutting the strip connecting their ends. The 25 angle of inclination of the supporting frame 1 and hence the speed of movement of the rolls of fabric may be adjusted by loosening the clamps 9 and varying the heights of the standards 6 as desired and the angle of the 30 table 13 may be changed to conform with the angle of the supporting frame 1, as previously noted.

Obviously the number of supporting rollers may be varied to suit the work for which 35 the machine is designed. While I have illustrated one form of stitch changing means it is to be understood that any other device having a member movable into different positions to effect changes in the lengths of the 40 stitches may be employed without departing from my invention.

I claim:—

1. The combination in a sewing machine of a stitch-changing device; driving mechanism; with a single member connected to said device and to the driving mechanism and operative to start the machine and change the length of the stitches.

2. The combination of a sewing machine 50 including a stitch-changing device; means for operating the sewing machine; a treadle for controlling said means, and connections between the stitch-changing device and the treadle, capable of being actuated while the 55 machine is in operation.

3. The combination of a sewing machine including a stitch-changing device; means for controlling the operation of the sewing machine; and a member connected to the 60 machine controlling means and to the stitch-changing device for successively throwing the machine into operation and changing the character of the stitches.

4. The combination in sewing mechanism 65 of a sewing machine having an inclined

table; a guide rail inclined at substantially the angle of the table and extending in the line of the stitches formed by the machine; and an inclined series of rollers extending adjacent the rail in position to guide a roll 70 of material past the sewing machine at substantially the level of the table thereof.

5. The combination in sewing mechanism, including a sewing machine, of a supporting structure; work supporting rollers mounted 75 thereon; a brake placed to act on certain of the rollers; a controlling member; means for automatically applying the brake to the rollers; and brake releasing means connected to said controlling member. 80

6. The combination in sewing mechanism, including a sewing machine, of a supporting structure; work supporting rollers mounted thereon; means for controlling the operation of the sewing machine; a brake placed 85 to act on certain of the rollers; a controlling member; means for automatically applying the brake; with means connecting the brake and machine controlling means to the controlling member whereby movement of the 90 latter releases the brake and starts the machine.

7. The combination in sewing mechanism of a sewing machine having an inclined work table; a supporting structure; a series of 95 work supporting rollers inclined at substantially the angle of said table and mounted to guide a roll of material past the same; with means for adjusting the supporting structure to change the angle of the series of 100 rollers relatively to that of the sewing machine table.

8. The combination, in sewing mechanism including a sewing machine having a table, of a supporting structure; an inclined series 105 of work supporting rollers mounted to guide a roll of material longitudinally past the sewing machine at substantially the level of its table; and means for adjusting the supporting structure to change the angle of 110 inclination of said series of rollers relatively to the sewing machine.

9. The combination in sewing mechanism, including a sewing machine having a work supporting table, of a supporting structure; 115 a series of rollers thereon for supporting the body portion of a fabric; and a rail mounted to extend substantially within the plane of the table of the machine and of the series of rollers for supporting an edge of the fabric to guide it under the needle of the sewing machine. 120

10. The combination in sewing mechanism, including a sewing machine, of a supporting structure; a series of rollers thereon for supporting the body portion of a fabric; a rail for supporting an edge of the fabric to guide it under the needle of the sewing machine; a table for supporting the sewing machine; and means for adjusting said table to bring 130

- the bed of the sewing machine into the plane of the supporting surface of said rail.
11. The combination in sewing mechanism, including a sewing machine, of a supporting structure; a series of supporting rollers thereon having their axes in an inclined plane; a rail for supporting the edge of said fabric and extending in a plane parallel with that of said rollers; means for adjusting the angle of inclination of the series of rollers; a table for supporting the sewing machine; and means for adjusting said table to bring the bed of the sewing machine into the plane of the work-supporting surface of said rail.
15. 12. The combination in sewing mechanism of a supporting structure; supporting rollers thereon; a sewing machine including stitch-changing mechanism; driving means for said sewing-machine; a treadle; a brake for the rollers; and means connecting said treadle with the brake, the stitch-changing devices and driving means so that a movement of the treadle in one direction releases the brake, throws the actuating means into operation and gradually changes the character of the stitch produced.
13. The combination in sewing mechanism of a supporting structure; fabric supporting rollers thereon having their axes in an inclined plane; a sewing machine including a stitch changing-device; means including a clutch for driving the sewing machine; a brake for the rollers; a treadle; means connecting the treadle with the brake, the stitch-changing device and the clutch so that a movement of the treadle in one direction releases the brake, actuates the clutch to drive the machine and moves the stitch-changing device to gradually vary the character of the stitches.
- 40 14. The combination of a supporting structure; supporting rollers having their axes in an inclined plane; a sewing machine including a stitch-changing device; means including a clutch for driving the machine; a brake for the rollers; a treadle; means for connecting the treadle with the brake; means for automatically applying the brake; a spring for automatically releasing the clutch; means for connecting said clutch with the treadle; and means connecting the stitch-changing device and the treadle, the arrangement of parts being such that movement of said treadle in one direction releases said brake, actuates said clutch to operate the machine and operates said stitch-changing device to vary the character of the stitches.
- 60 15. The combination of a supporting structure; supporting rollers having their axes in an inclined plane; a sewing machine including a stitch-changing device; means
- including clutch mechanism for driving the machine; a brake for the rollers; a treadle; means connecting the treadle with the 65 brake; means for automatically applying the brake; a spring for automatically releasing the clutch; resilient means connecting said clutch mechanism with the treadle; and means connecting the stitch-changing 70 device and the treadle whereby movement of said treadle in one direction releases said brake, actuates said clutch to drive the machine and operates said stitch-changing device to vary the character of the stitches. 75
16. The combination of a supporting structure; supporting rollers having their axes in an inclined plane; a sewing machine including clutch mechanism for driving the 80 machine; a brake for the rollers; a treadle; means connecting the treadle with the brake; means for automatically applying the brake; a spring for automatically releasing the clutch; means connecting said clutch 85 mechanism with the treadle; means connecting the stitch-changing device and the treadle whereby movement of said treadle in one direction releases said brake; actuates said clutch to operate the machine and operates said stitch-changing device to vary 90 the character of the stitches; and means for automatically returning the stitch-changing device to its normal position.
17. The combination in sewing mechanism of a rail made in two portions spaced apart; a sewing machine extending into the space between said rail portions with its table at the level of the rail; and a series of rollers extending substantially parallel to 100 the line of the rail with their uppermost portions immediately adjacent the plane of the sewing machine table, in position to guide a body of material thereby.
18. The combination of a rail formed in 105 two portions spaced apart; a sewing machine having a table extending into the space between said portions; with a series of rollers tapering from their ends toward their middle portions and extending in a 110 line past the table of the sewing machine, said series of rollers, the rail and the table being all inclined at an angle to permit movement of a roll of material on the rollers past the machine under the action of 115 gravity.
